LINER PULLER

William A. Redell and John M. Wiley, Arkansas City, Kans., assignors to The Farley Machine Works Co., Arkansas City, Kans., a corporation of Kansas

Application January 3, 1938, Serial No. 183,184

2 Claims. (Cl. 29—88.2)

This invention relates to pullers for dislodging and removing liners or sleeves from cylinders of pumps or other like equipment.

An object of the invention is to provide novel means for applying a maximum power, compared with known devices for such use, to definitely defined parts or locations of an object to be moved, the said means being adaptable to a wide range of utility with respect to pumps or other equipment.

10 It is a further object of the invention to provide a liner puller that will not injure the liner; and furthermore, to provide means to facilitate the positioning of the puller in exact relationship with the liner to insure substantially equal gripping action of the jaws as they engage the liner; the said means furthermore enabling an operator to be assured of the correct positioning of the puller with relation to the liner.

15 It is furthermore an object of the invention to provide a puller of the character noted which is efficient and satisfactory in use and comparatively inexpensive to produce and maintain.

20 With the foregoing and other objects in view, the invention consists in the details of construction, and in the arrangement and combination of parts to be hereinafter more fully set forth and claimed.

25 In describing the invention in detail, reference will be had to the accompanying drawing forming part of this application, wherein like characters denote corresponding parts in the several views, and in which—

Figure 1 illustrates a view in elevation of the puller;

30 Figure 2 illustrates a similar view at right angles to that of Fig. 1;

Figure 3 illustrates a sectional view on the line 3—3 of Fig. 2;

Figure 4 illustrates a sectional view on the line 35 4—4 of Fig. 2;

Figure 5 illustrates a sectional view on the line 40 5—5 of Fig. 2;

Figure 6 illustrates a sectional view of a quadrant and parts associated therewith; and

45 Figure 7 illustrates a sectional view of the body and parts associated therewith.

In describing the invention, it will be inferred that the puller is operated when in a substantially vertical position, to justify a reference in the specification to the "upper and lower ends" of the parts, but obviously, pullers of this type are used very often in a horizontal or other position.

In the drawing 10 denotes a stem or mandrel threaded a suitable distance from its upper end 50 toward its lower end, the said mandrel being

swivelled at its lower end through the medium of a flange 11 on said lower end, rotatable in a groove 12 formed in the apertured body 13, the aperture thereof being at the top of the body so that the mandrel projects therethrough. The aperture 14 of the body is larger in diameter than the mandrel and is threaded to engage the threads of the sleeve 15 on the mandrel so that the sleeve is stationarily held with relation to the body. The body is provided with radial slots 16 in its lower portion, in which gripping jaws 17 are slideable radially so that they project from the periphery of the body and are forced into engagement with the liner to be drawn.

15 A bottom plate 18 is applied to the body and is held in place by studs 19 threaded in the body. Each jaw has a diagonally disposed slot 20 and the lower end of the mandrel has pins 21, one of which projects through a slot 20 and, as shown in Figure 5, when the mandrel is turned, the pins 20 will exert a camming action on the walls of the slot 20 and move the jaws radially, according to the direction of rotation of the mandrel. In Figure 5 the jaws are shown as being in their outermost position and will be drawn inwardly 25 upon rotation of the mandrel in the direction of the arrow A of Fig. 5.

The body is provided with a peripherally positioned filler bushing 22 having slots 23 registering with the slots of the body, and it is the purpose of 30 the inventors that these bushings shall be of different diameters to fit the interior of the liner to be pulled and to accurately center the body with relation to the internal diameter of the liner, so that the pull exerted when drawing the liner 35 will be a straight pull and the force of the jaws on the liner will be equally distributed.

The sleeve 15 is circumferentially slotted, as at 24, to form a clearance, in which an arm 25 projects into a threaded aperture 26 of the mandrel, 40 and the said arm is held at different positions of adjustment through the medium of a detent or pin 27 which may enter any one of a plurality of slots 28 in the flange 29 of a bracket 30, which bracket is secured on the sleeve by a fastening 45 31, such as a screw or the like. The pin is under the tension of a spring 32 which holds it in its adjusted position, it being obvious that the pin has a hand grip 33 on its upper end by which the pin is raised or manipulated and the arm moved in 50 adjusting the mandrel and consequently the positions of the jaws with relation to the body.

A cross-bar 34 of appropriate construction has an aperture through which the mandrel projects, and a nut 35 is threaded on the mandrel. A race- 55

way 36 for anti-friction rollers 37 is interposed between the nut and cross-bar, and when the nut is screwed on the mandrel while the cross-bar is suitably supported by reason of its spanning the end of pump against which the power of the nut is applied, the liner is dislodged and drawn. The cross-bar is preferably reinforced by ribs 38 to insure strength and durability.

It is obvious that filler bushings of different diameters may be substituted, but only one such bushing is illustrated, though the others may be the same construction except as to thickness, and it is shown on the drawing that the lower edge of the bushing rests on a shoulder 39 of the plate 18.

We claim:

1. A liner puller comprising a mandrel, a body in which the lower end of the mandrel is swiveled, a sleeve on the mandrel attached to the body, 20 said sleeve having a circumferential slot, an arm movable in the slot and secured to the mandrel for turning the same, means for holding the arm in different positions of adjustment, jaws slidable radially in the body, said jaws having diagonal 25 slots near their inner ends, projections on the

mandrel extending into said slots acting on the camming edges of the slots to project and retract the jaws as the mandrel is rotated, and means for exerting a pull on the mandrel longitudinally thereof.

2. A liner puller comprising a mandrel, a body in which the lower end of the mandrel is swiveled, a sleeve on the mandrel attached to the body, said sleeve having a circumferential slot, an arm movable in the slot and secured to the mandrel for turning the same, means for holding the arm in different positions of adjustment, jaws slidable radially in the body, said jaws having diagonal slots near their inner ends, projections on the mandrel extending into said slots acting on the 15 camming edges of the slots to project and retract the jaws as the mandrel is rotated, threads on the mandrel near its upper end, a cross-bar to be supported through which the mandrel is movable, a nut on the mandrel above the cross-bar for 20 pulling the cross-bar, and anti-friction elements between the nut and cross-bar.
